E. A. SMITH.

DOOR.

APPLICATION FILED DEC. 12, 1918.

1,346,268.

Patented July 13, 1920.

Fig. 1.

Fig 2.

A technical line drawing of a building's cross-section. The drawing shows a central horizontal wall section labeled '30'. On the left, there is an entrance labeled '20' with a door labeled '41' above it. On the right, there is another entrance labeled '20' with a door labeled '41' above it. The left side of the drawing is labeled with '14' at the bottom, '42' at the top left, '13' above '42', '40' to the right of '13', and '10' at the bottom left. The right side of the drawing is labeled with '43' at the top right, '15' below '43', '34' to the right of '15', and '16' at the bottom right. The top of the drawing features a wavy line with the label '43' at both ends.

UNITED STATES PATENT OFFICE.

EDWARD A. SMITH, OF NEW YORK, N. Y.

DOCC.

1,346,268.

Specification of Letters Patent. Patented July 13, 1920.

Application filed December 12, 1918. Serial No. 266,502.

To all whom it may concern:

Be it known that I, EDWARD A. SMITH, a citizen of the United States of America, and a resident of New York, county of Bronx, 5 and State of New York, have invented certain new and useful Improvements in Doors, of which the following is a specification, reference being had to the accompanying drawings, forming a part thereof.

10 My invention relates to new and useful improvements in doors, such as are particularly adapted for closing the openings of elevator hatchways, and its object is to provide a simple and inexpensive support for 15 doors of this character, by means of which they are guided laterally as well as vertically. More specifically, its object is to provide a rigid door which forms a fire-proof closure for hatchway openings and which 20 when raised vertically, is moved inwardly to pass between projections such as sills and the elevator car.

In order that my invention may be thoroughly understood I will now proceed to 25 describe the same in the following specification, and will then point out the novel features thereof in appended claims.

Referring to the drawings:

Figure 1 is a front elevation of a plurality of doors and supports therefor which 30 embody this invention, together with parts of a hatchway structure shown in section.

Fig. 2 is a sectional side elevation of the 35 same parts with the outline of an elevator car shown in broken lines.

Fig. 3 is a sectional plan view of the parts shown in Fig. 1.

Like characters of reference designate corresponding parts in all the figures.

40 10 designates the walls of a building adjacent an elevator hatchway. 11 designates the floors of such a structure of which the portions 12 form the thresholds or sills projecting into the hatchway. An angle iron 13 is secured to the wall 10 and another angle iron 14 secured thereto to form a box-like structure which incloses a counterweight 40. A similar arrangement is provided on the opposite side of the doorway.

50 Secured to the parallel surfaces of the parts 14 on opposite sides of the doorway are channel guides 20 which are vertically disposed throughout the greater part of their length. The lower end of each channel guide is bent outwardly as at 21 and continued a short distance below this bend

to form lower vertical part 22 which, if desired, may be bent outwardly at its end as shown at 23.

Above the bend 21 of each channel is a 60 straight part 24 which is vertical. At 25 is an inward bend at about the center of the length of each guide, above which is another straight vertical portion 26. The lower parts 23 of the guides are in vertical alignment with one another while the part 26 of each guide overlaps and is parallel with the part 24 of the adjacent guide next above it.

The doors 30 are rigid structures of metal or wood. If of wood they are preferably 70 sheathed with metal to give them a fire-resisting character. At the lower corners of the door are inwardly projecting rigid brackets 31 near the ends of which are rollers 32 which run in one of the guides 20. 75 Above the brackets 31, in alignment therewith and spaced a substantial distance from them are other rigid brackets 33 which carry rollers 34 in another of the guides.

Such doors are usually counterbalanced 80 and any suitable arrangement for this purpose may be used. In the drawings the counterweights 40 are shown with cables 41 running from them, up over stationary sheaves 42 and down to the lower corners of 85 the doors to which they are attached at 43.

The operation of this device will be made clear from the following description. The 90 length of the brackets 31 is as much greater than the length of the brackets 33 as the distance of the center line of the parts 24 of the guides 20 from the plane of the closed door is greater than the distance of the center line of the parts 22 from the same plane. Consequently, the door will be held in a 95 vertical position. The brackets 31 and 33 are spaced apart a distance equal to the vertical distance between the bends 21 and 25. The result is that when the door 30 is raised its rollers 34 will reach the bends 24 at the 100 same time its rollers 32 reach the bends 25. A continued lift of the door will cause the rollers 34 to pass through the bends 21 into the guide parts 24 and at the same time its rollers 32 will pass through the bends 25 105 into the guide parts 26. During this part of the operation the door will be moved obliquely inwardly but will still be maintained in a vertical position. Further lift of the door will cause it to move up vertically between the projecting sill 12 and the adjacent side of the elevator car which is designated

in Fig. 2 by the reference numeral 50, into some such position as that in which it is shown in dot and dash lines at 30^A in Fig. 2.

In lowering the door the operation is reversed and the door brought to its closing position with its lower edge resting upon the threshold and with its upper part against the lintel as at 15. When the lower ends of the guides are bent outwardly as at 23 this causes the upper part of the door to exert a pressure against the lintel.

I intend no limitations other than those imposed by the appended claims.

What I claim is:

- 15 1. A door, guides therefor at opposite sides of the door opening, rigid brackets projecting from the door near the edges thereof, said brackets being spaced vertically a fixed distance, and members on said brackets arranged to be engaged by and to move in the guides, said guides having offset portions spaced vertically the same distance as that between the brackets, arranged to impart a transverse bodily sliding movement 25 to the door when said door is moved vertically.
- 20 2. A door, a pair of guides therefor at each side of the door opening in parallel relation, rigid brackets projecting from the door near opposite edges thereof and a member of each bracket arranged to be engaged by and to move in one of said guides, other rigid brackets above said first mentioned brackets, and a member on each of said other brackets arranged to be engaged by and to move in the other of said guides, the two guides on either side of the door opening having offset portions spaced vertically the same distance as the vertical distance between the brackets on the corresponding side of the door and arranged to impart a transverse bodily sliding movement to the door when said door is moved vertically.
- 25 3. A door, a pair of overlapping guides therefor at each side of the door opening, rigid brackets projecting from the door near the lower corners thereof, a roller on each bracket arranged to be engaged by and to move in one of said guides, other rigid brackets above said lower brackets, and a roller on each of said other brackets, a shorter distance from the surface of the door than that of the rollers on the lower brackets, arranged to be engaged by and to move in the other of said guides, the two guides on either side of the door opening having offset portions spaced vertically the same distance as the vertical distance between the brackets on the corresponding side of the door and arranged to impart a transverse bodily sliding movement to the door when said door is moved vertically.

tions spaced vertically the same distance as the vertical distance between the brackets on the corresponding side of the door and arranged to impart a transverse bodily sliding movement to the door when said door is moved vertically.

4. A door, a pair of overlapping guides therefor at each side of the door opening, rigid brackets projecting from the door near the lower corners thereof, a roller on each bracket arranged to be engaged by and to move in one of said guides, other rigid brackets above said lower brackets, and a roller on each of said other brackets, a shorter distance from the surface of the door than that of the rollers on the lower brackets, arranged to be engaged by and to move in the other of said guides, the two guides on either side of the door opening having offset portions spaced vertically the same distance as the vertical distance between the brackets on the corresponding side of the door and arranged to impart a transverse bodily sliding movement to the door when said door is moved vertically, the lower ends of the guides which engage the rollers on the upper brackets being bent outwardly.

5. A plurality of doors in vertical alignment, overlapping guides therefor at each side of the door openings, rigid brackets projecting from each door near the lower corners thereof, a roller on each bracket arranged to be engaged by and to move in one of said guides, other rigid brackets above said lower brackets and a roller on each of said other brackets, a shorter distance from the surface of its door than that of the rollers on the lower brackets on the same door, arranged to be engaged by and to move in the other of said guides, two guides on either side of each door opening having offset portions spaced vertically the same distance as the vertical distance between the brackets on the corresponding side of the adjacent door and arranged to impart a transverse bodily sliding movement to the door when said door is moved vertically, the lower end of each guide being arranged to receive the rollers on the upper brackets of one door and the rollers on the lower brackets, and having a portion adapted to receive the rollers on the lower brackets of the next door above.

In witness whereof, I have hereunto set my hand this 16 day of October, 1918.

EDWARD A. SMITH.
